(57) **CLAIM**

The ornamental design for a frame for a combined table and benches, as shown and described.

DESCRIPTION

FIG. 1 is a bottom perspective view of a frame for a combined table and benches showing my new design;

FIG. 2 is a top view thereof;

FIG. 3 is a side elevation view thereof looking from the right of FIG. 2;

FIG. 4 is a bottom view thereof; and,

FIG. 5 is a side elevation view thereof displaced 45° from FIG. 3.

Side elevation views displaced in 90° increments from FIGS. 3 and 5 are identical.

Perspective views displaced in 90° increments from FIG. 1 are identical.

The table top and benches shown in dashed lines form no part of the design.
